TAPE CARTRIDGE STORING, SELECTING AND READING UNIT

Arnold M. Davis and David Wassertheil, Poughkeepsie,
N.Y., assignors to International Business Machines Cor-
poration, New York, N.Y., a corporation of New York

Filed Mar. 10, 1961, Ser. No. 64,373

Term of patent 14 years

(Cl. D26—5)

FIG. 1

Des. 193,512

PAGE 2

FIG. 3

FIG. 4

FIG. 1 is a front elevation of the tape cartridge storing, selecting and reading unit.

FIG. 2 is a right side elevation of the unit, the left hand side being identical.

FIG. 3 is a rear elevation of FIG. 1, and

FIG. 4 is a plan view of the unit.

The characteristic features of our design reside in the composite unit comprising two tape readers with transparent top and bottom panels, two storages each having transparent top panels, a selector also having top and bottom transparent panels all panels being framed in shiny

metallic strip, all members except the selector having ventilating grilles in the top and the selector having a transparent panel in the rear all as shown.

We claim:

The ornamental design for a tape cartridge storing, selecting and reading unit, as shown and described.
